UNITED STATES PATENT OFFICE.

LEMUEL WILLIAM SERRELL, OF PLAINFIELD, NEW JERSEY, ASSIGNOR TO THE VA-CUNA COMPANY, OF EAST ORANGE, NEW JERSEY, A CORPORATION OF NEW JERSEY.

DUST-SEPARATING OR VACUUM CLEANING APPARATUS.

964,940.

Specification of Letters Patent. Patented July 19, 1910.

Application filed September 16, 1907. Serial No. 392,981.

To all whom it may concern:

Be it known that I, LEMUEL WILLIAM SERRELL, a citizen of the United States, residing at Plainfield, in the county of Union 5 and State of New Jersey, have invented an Improvement in Dust-Separating or Vacuum Cleaning Apparatus, of which the following is a specification.

My invention relates in connection with 10 pneumatic or vacuum cleaning devices, to means for moistening the dust of dust laden air previous to its passage into the wash box or liquid holding vessel, so as to insure a quick and ready mixture with, and taking 15 up in suspension by the water of the wash box and the liberation of the cleaned air.

The device of my invention is located in 20 the pneumatic or vacuum cleaning apparatus in the line of pipe between the place where the dust is collected and the wash box into which it is delivered, and in carrying out my invention, I employ a circular mixing vessel composed of two connected parts, 25 into one of which a pipe enters for conveying the dust laden air or dirty water; the other or lower part of this mixing vessel is provided with a raised flanged center and lower chamber merging into a discharge pipe. A tubular boss enters this 30 lower chamber and a pipe for water is connected therewith on the outside and the pipe of an internal member is connected to it on the inside and this internal member is composed of a disk and top plate and into 35 the cavity formed between these parts, the water enters and is discharged by peripheral or marginal holes. This internal member is formed with a disk which fits tightly within the main vessel and the periphery of the 40 disk is diagonally grooved or provided with ports through which the dust laden air or dirty water passes with appreciable and increased speed. The water holes preferably align with the discharge openings of these 45 diagonal ports so that the dust of the dust laden air in passing through these diagonal ports, produces an atomizing effect upon the water and the dust is wet by the particles of the immersing water, so that the dust with 50 the water and air all pass together down into the wash box or liquid holding vessel.

In the drawing, Figure 1 is a vertical section representing the devices of my improvement. Fig. 2 is a plan of the disk 55 portion of the internal member with its

flange, and Fig. 3 a side elevation of the parts shown in Fig. 2.

a represents the upper part or member of the circular mixing vessel of dome shape with a flanged lower edge, and *2* a pipe 60 which enters the apertured center of said member for conveying into said vessel the dust laden air as gathered in cleaning, or dirty water collected in cleaning.

b represents the lower part or member of 65 the circular mixing vessel with a flanged edge adapted to be connected to the flanged edge of the upper member, as shown in Fig. 1. This lower member is provided with a central circular flange *b*¹ rising from the bottom of the vessel with a central discharge chamber *3* of small area in proportion to that of the mixing vessel. A tubular boss *b*² extends into the discharge chamber and is internally threaded at its outer end to receive the pipe 6 for water and axially bored and threaded to receive the center pipe *c*² and the lower end or part of the mixing vessel *b* is apertured and threaded to receive the discharge pipe 4. 70

c represents a disk formed in one piece with a center pipe *c*² with a rising outer and flanged edge *c*¹. This disk is provided with bosses bored and threaded for the bolts 7 which secure to the disk the top plate *d*, 85 thus forming between the disk *c* and the top plate a water chamber to receive the water which enters by the pipe 6, the longitudinal passage-way 5 in the boss *b*² and through the center pipe *c*² and the disk is provided 90 with series of small water holes 8 from which this water is discharged into the mixing vessel. The periphery of the flanged edge *c*¹ of the disk *c* is diagonally grooved to provide surface ports 9. These 95 agree by preference in number with the number of the water holes 8 and their lower discharge ends substantially coincide with the mouths of these water holes. These diagonal ports form the only communicating 100 passage-ways between the upper part of this circular mixing vessel and the lower part, consequently the entire volume of dust laden air or dirty water is obliged to pass through these diagonal ports and in 105 doing so, a circular motion at an increased speed is imparted thereto and the dust of the dust laden air is moistened by the water which immerses with some force from the holes 8, an atomizing effect having been 110

given to the water. The supply of water passing through these holes from the pipes 6 and c^2 is preferably under control and serves to replenish the water in any suitable water tank or liquid holding vessel and cause an overflow of the same with the object of keeping this liquid holding vessel as clean as possible. As the area of the discharge chamber 3 is small compared with 10 that of the mixing vessel, this outlet causes a rapid action of the air and dust or dirty water as the same passes therethrough, which prevents lodgment of dirt.

In an application filed by me of even date 15 herewith, I have shown and generally described the features of the present application, as I prefer to employ the devices of this application in connection with the apparatus of my copending application.

20 In the device of my improvement and where dirty or soapy water is being collected in cleaning, the water discharged from the water holes 8 serves to dilute this dirty water and at the same time increase the 25 bulk of the water in the wash box or liquid holding vessel, so as to keep up the flow in said vessel and the continuous discharge of the dirty water into the sewer.

I claim as my invention:

30 1. In a pneumatic or vacuum cleaning apparatus and in combination, a pipe for the dust laden air, a vessel interposed in the line of and connected to adjacent sections of said pipe, a device within and extending across said vessel adapted to receive water, having openings connecting the chambers of said vessel at the opposite sides thereof for the passage of the dust laden air and also provided with openings for delivering 40 the water therefrom to be commingled with and moisten the dust.

2. In a pneumatic or vacuum cleaning apparatus and in combination, a pipe for the dust-laden air, a vessel interposed in 45 the line of said pipe carried thereby and of appreciably greater diameter than said pipe, a structure within and extending across said vessel that is in part hollow and is provided with peripheral openings between the same and the walls of said vessel for the passage of the dust-laden air and also provided with openings in the hollow walls thereof adjacent to the peripheral openings, and means adapted to 50 bring water into the hollow part of said structure under some pressure for its delivery to be commingled with and moisten the dust of the dust-laden air after passage through said peripheral opening.

60 3. In a pneumatic cleaning apparatus and in combination, a central pipe for the dust laden air, a hollow vessel interposed in the length of said pipe, a hollow diaphragm for water within said vessel having 65 openings for discharging and distributing

the water therefrom, means for conveying water into said hollow diaphragm and said diaphragm provided with inclined peripheral grooves for the passage of the dust laden air whereby a circular motion and 70 agitation is imparted to the air and water before passing out from the said hollow vessel.

4. In a pneumatic or vacuum cleaning apparatus, the combination with the pipe for 75 conveying dust laden air or dirty water thereto, of a vessel or chamber composed of two separate connected parts introduced into the line of said pipe, a device inserted within and extending across said vessel, 80 means for introducing water into said device and said device provided with means for discharging the water therefrom and also means providing for the passage of the dust laden air or dirty water from one side 85 of the said device to the other through said vessel and which latter means are in alignment with the means for discharging the water, whereby an atomizing effect is produced upon the issuing water by which the 90 dust of the dust laden air is moistened by the water in its passage through the vessel.

5. In a pneumatic or vacuum cleaning apparatus, the combination with the pipe for conveying dust laden air or dirty water 95 thereto, of a vessel or chamber composed of two separate connected parts introduced into the line of said pipe, a hollow member placed within said vessel and snugly fitting the internal diameter thereof and having a 100 central pipe, a passageway and pipes communicating therewith for supplying water within the said member, discharge passageways for the water from said member and peripheral ports in said member through 105 which the dust laden air or dirty water passes to be commingled with the discharge water from the said member within said vessel.

6. In a pneumatic or vacuum cleaning apparatus, the combination with the pipe for 110 conveying dust laden air or dirty water thereto, of a vessel or chamber composed of two separate connected parts introduced into the line of pipe, a tight fitting hollow member introduced into said vessel or chamber having a pipe for water, means for supplying water to this pipe to be passed into said member, discharge apertures in said member through which the water passes 115 into said vessel, diagonal peripheral grooves in the edges of said tight fitting member through which the dust laden air is rapidly drawn and in its passageway given a rotary motion, the exit openings of said grooves 120 being in proximity to the discharge openings for the water, so that the water exit from said member comes below the outlets of said grooves, whereby the dust of the dust laden air is wet by the discharging water 125 130

and the force of the inrushing air will act to blow said water into fine streams or a comminuted condition which assists in thoroughly wetting the dust.

5 7. In a pneumatic or vacuum cleaning apparatus, the combination with the pipe for conveying dust laden air or dirty water thereto, of a vessel or chamber composed of two separate connected parts introduced into 10 the line of said pipe, a tight fitting hollow member introduced into said vessel or chamber having a pipe for water, means for supplying water to this pipe to be passed into said member, discharge apertures in said 15 member through which the water passes into said vessel, diagonal peripheral grooves in the edges of said tight fitting member through which the dust laden air is rapidly drawn and in its passageway given a rotary 20 motion, the exit openings of said grooves being in proximity to the discharge openings for the water, so that the water exit from said member comes below the outlets of said grooves, whereby the dust of the dust laden 25 air is wet by the discharging water and the force of the inrushing air will act to blow said water into fine streams or a comminuted condition, which assists in thoroughly wetting the dust, a narrow central discharge 30 chamber formed in the lower part of said vessel and through which the dirty water or the air and moistened dust must pass.

8. In a pneumatic or vacuum cleaning apparatus, the combination with the pipe 35 through which dirty water or dust laden air passes thereto, of a vessel interposed in said line of pipe and comprising an upper portion and flanged edge, a lower portion and flanged edge connected together, an internal 40 central circular rising flange formed with the lower portion of said vessel, a discharge chamber narrow in diameter in the lower part of said vessel, a longitudinal apertured boss entering the lower discharge chamber, 45 a pipe for entering water alining with the passageway in the said boss, a pipe for discharging water from the passageway in said boss, a hollow member tightly fitting said vessel and preferably formed with the latter 50 water pipe for conveying water into said hollow member, discharge passageways from said hollow member for the water, peripheral grooves forming passageways for the dirty water or dust laden air from the 55 upper to the lower part of said vessel, the lower parts of which are in proximity to the passageways for the water, whereby the air rushing through comminutes the emerging water into a spray that wets the dust.

60 9. In a pneumatic or vacuum cleaning apparatus, the combination with the pipe through which dirty water or dust laden air passes thereto, of a vessel interposed in said line of pipe and comprising an upper 65 portion and flanged edge, a lower portion

and flanged edge connected together, an internal central circular rising flange formed with the lower portion of said vessel, a discharge chamber narrow in diameter in the lower part of said vessel, a longitudinal 70 apertured boss entering the lower discharge chamber, a pipe for entering water alining with the passageway in the said boss, a pipe for discharging water from the passageway in said boss, a disk *c* having a rising portion 75 through which holes 8 are formed and spaced apart and a flanged edge *c*¹, said disk being formed integrally with the last aforesaid water pipe, a top plate *d* adapted to be secured to said disk so as to form of the 80 disk and the top plate a hollow member snugly fitting within said chamber, diagonal surface grooves 9 in the said flanged edge of the disk, through which the dirty water or dust laden air must pass and by which a 85 rotary motion is imparted to the dust laden air, the lower ends of said diagonal grooves being in proximity to the discharge water openings 8 in the disk whereby the discharged water is comminuted or blown to a 90 spray so as to thoroughly wet the dust of the dust laden air.

10. In a pneumatic or vacuum cleaning apparatus, the combination with the pipe 95 through which dirty water or dust laden air passes thereto, of a vessel interposed in said line of pipe, a discharge chamber narrow in diameter in the lower part of said vessel, a longitudinal apertured boss entering the lower discharge chamber, a pipe for entering 100 water alining with the passageway in the said boss, a pipe for discharging water from the passageway in said boss, a hollow member tightly fitting said vessel and formed with the latter water pipe for conveying 105 water into said hollow member, discharge passageways from said hollow member for the water, peripheral grooves forming passageways for the dirty water or dust laden air from the upper to the lower part of said vessel, the lower parts of which are in proximity to the passageways for the water, whereby the air rushing through comminutes the emerging water into a spray that wets 110 the dust.

11. In a pneumatic or vacuum cleaning apparatus, the combination with the pipe through which dirty water or dust laden air passes thereto, of a vessel interposed in said line of pipe, a discharge chamber narrow in 120 diameter in the lower part of said vessel, a longitudinal apertured boss entering the lower discharge chamber, a pipe for entering water alining with the passageway in the said boss, a pipe for discharging water from the passageway in said boss, a disk *c* having a rising portion through which holes 8 are 125 formed and spaced apart and a flanged edge *c*¹, a top plate *d* adapted to be secured to said disk so as to form of the disk and the 130

top plate a hollow member snugly fitting within said chamber, diagonal surface grooves 9 in the said flanged edge of the disk, through which the dirty water or dust laden air must pass on its way to the cleaning apparatus and by which a rotary motion is imparted to the dust laden air, the lower ends of said diagonal grooves being in proximity to the discharge water openings 8 in 10 the disk whereby the discharged water is

commminuted or blown to a spray so as to thoroughly wet the dust of the dust laden air.

Signed by me this 6th day of September 1907.

LEMUEL WILLIAM SERRELL.
